UNITED STATES PATENT OFFICE.

WALTER E. PARMELEE, OF MERIDEN, CONNECTICUT.

ARCH-SUPPORT.

1,146,899.

Specification of Letters Patent. Patented July 20, 1915.

Application filed April 22, 1914. Serial No. 833,787.

To all whom it may concern:

Be it known that I, WALTER E. PARMELEE, citizen of the United States, residing at 22 South Second street, city of Meriden, in the 5 county of New Haven and State of Connecticut, have invented certain new and useful Improvements in Arch-Supports, of which the following is a specification.

One object of the invention is to provide 10 a device of the class specified adapted to give comfort to the wearer.

A further object of the invention is to provide a support for weak joints or broken arches of the foot, which is of sufficient 15 rigidity to accomplish this purpose without the use of metal, as metal often causes discomfiture, is too rigid and has a tendency to break, thereby injuring the foot as well as ordinarily being too clumsy and heavy.

20 A further object of the invention is to provide a foot support adapted to hold in their relatively proper and normal positions the tarsal and metatarsal joints of the foot.

To these ends and also to improve generally on devices of the class specified the invention consists in the various matters hereinafter described and claimed.

Fig. 1 is a perspective view of the device with the covering thereon. Fig. 2 is a bottom view without the covering. Fig. 3 is a top view without the covering. Fig. 4 is a perspective view of the strip.

The device is of the general type of a device commonly known as an arch supporter.

35 Referring to the drawings as an illustrated embodiment of the invention, a strip of material —1— as shown in Fig. 4 is made of suitable material such as leather of sufficient thickness to hold its shape and be 40 somewhat stiff yet flexible for the comfort of the wearer. The strip —1— is preferably shaped to fit the arch under the tarsal joint of the foot and adapted to extend forward a trifle beyond the metatarsal joint of the foot.

45 A substantially rigid member —2— made preferably of sole leather and cut to proper shape is suitably secured to the strip —1— under the main arch or tarsal joint of the foot, being located somewhat on the inner 50 side of the strip —1—, as the drawing shows

a support for the left foot. The lower surface of the member —2— is substantially in the same plane as the respective ends of the strip —1—. A member —3— also substantially rigid preferably made of sole leather 55 but of less thickness than the member —2—, is suitably secured to the strip —1— and preferably on top thereof, as shown in Fig. 3, so as to be located beneath the metatarsal joint of the foot.

60 It will be seen that by reinforcing the strip —1— by the members —2— and —3— that the support itself, where thus reinforced, is substantially rigid but, where not thus reinforced, is flexible for the comfort of the 65 wearer. The members —2— and —3— are relatively adjacent each other but far enough apart so that the support itself is flexible between the said members —2— and —3— and may be twisted or bent to comply with 70 the action of the foot and relative movements of the sole of the shoe. The members —2— and —3— are preferably cemented to the strip —1— and a suitable covering of smooth leather covers the whole support. 75 The support itself is not intended to be permanently secured in the shoe like an inner sole, but is used as customary arch supporters are used.

80 The device has no metal in its construction which might break and cause discomfiture, but is light and durable and provides proper rigidity and yet is sufficiently flexible at the proper places to insure comfort for the wearer.

85 What I claim is:

1. A non-metallic arch support consisting of a strip of suitable material shaped to fit the foot, a more rigid member secured to said strip under the tarsal joint of the foot, 90 and a member more rigid than said strip secured thereto under the metatarsal joint of the foot, the parts being so arranged that said support is rigid at the reinforced sections thereof, but flexible between the reinforced sections for the comfort of the wearer, substantially as described.

2. A non-metallic arch support consisting of a strip of flexible material, shaped to fit the arches of the foot, said strip being rein- 100

forced under the tarsal and metatarsal joints of the foot by a member more rigid than the strip itself, so arranged that the support is substantially rigid where thus reinforced, said reinforced sections of said support being relatively adjacent each other but arranged sufficiently apart to allow the support to be flexible between said rein-

forced sections for the comfort of the wearer, substantially as described. 10

In testimony whereof I affix my signature in presence of two witnesses.

WALTER E. PARMELEE.
